2 Sheets-Sheet 2

UNITED STATES PATENT OFFICE.

OTHO NILE BRAUN, OF MONTGOMERY, LLOYD FRANK NICHOLS, OF HANDLEY, AND ELMER LEE UNDERWOOD, OF LONDON, WEST VIRGINIA.

MAIL-BAG-DELIVERING APPARATUS.

Application filed July 3, 1922. Serial No. 572,597

To all whom it may concern:

Be it known that we, OTHO N. BRAUN, LLOYD FRANK NICHOLS, and ELMER L. UNDERWOOD, citizens of the United States, residing, respectively, at Montgomery, Handley, and London, in the counties of Fayette and Kanawha and State of West Virginia, have invented certain new and useful Improvements in Mail-Bag-Delivering Apparatus; and we do declare the following to be a full, clear, and exact description of the invention, such as will enable others skilled in the art to which it appertains to make and use the same.

15 This invention relates to an improved mail bag delivering apparatus and one object of the invention is to provide a mail bag delivering apparatus in which the bag holding means may normally hang in a substantially vertically disposed position where it will be out of the way and not liable to strike passengers who may be looking out of the windows of the cars.

Another object of the invention is to so 25 construct this mail bag delivering apparatus that the bag holding means may be moved to an extended position while the train is passing the station and removing the mail bag from the holding apparatus.

30 Another object of the invention is to so construct this mail bag delivery apparatus that the bag-holding apparatus may be swung into the operative position by means of links which are connected with a push bar mounted longitudinally of a track rail and normally positioned close to a hand-grip which extends longitudinally of the rail.

Another object of the invention is to so 40 construct this bag delivering means that it may be moved to extend the bag holding apparatus only when a train carried element for engaging the push bar is moved to an operative position by an operator within the car.

Another object of the invention is to provide a device which will be simple in construction and efficient in operation.

This invention is illustrated in the accompanying drawings, wherein:

Figure 1 is a top plan view showing the mail bag delivering apparatus in the normal position.

Figure 2 is a fragmentary view showing 55 the mail bag delivering apparatus partially

in top plan and partially in section and showing the push bar moved away from the cam bar by the train-carried means.

Figure 3 is a view taken along the line 3-3 of Fig. 1.

Figure 4 is a view similar to Fig. 3 showing the bag holding means moved to the operative position.

Figure 5 is a sectional view taken along the line 5-5 of Fig. 1.

This mail bag holding apparatus is to be mounted at a station or other point of delivery adjacent the railroad tracks and will be provided with a standard 1 which in the present illustration is in the form of vertically disposed bars connected by a cross bar 2 at their upper ends. This standard is mounted upon a suitable support or foundation which has been illustrated as supporting bars 3 from which extend the spaced vertically disposed bars 1 of the standard. These foundation-forming bars 3 may, if desired be extended beneath the rails of the track and take the place of rail supporting ties. At their outer ends, the supporting bars 3 are provided with upstanding arms 4 which carry guides 5 which serve to guide and limit the sliding and tilting movement of the rods 6. These rods 6 extend longitudinally of the bars 3 and in addition to being passed through the guiding brackets 5 are also passed through eyes 7 which are carried by the side bars 1 of the standard and serve as fulcrums for these rods 6. It will thus be seen that the rods may be moved longitudinally through the guides 4 and 7 and may also be rocked with the eyes 7 forming fulcrums and tilted from the position shown in Fig. 3 to that shown in Fig.

4 and then back again to the initial position shown in Fig. 3. These push and pull rods 6 have their rear ends pivotally connected with the links or rods 8 which extend upwardly and are connected with the lever handles 9 carried by the rocker shaft 10 journalized in the upper end portions of the side bars 1 of the standard. A sleeve 11 is carried upon the rocker shaft and since the rocker shaft and shaft-receiving passage of the sleeve are non-circular as shown in Figs. 3 and 4, this sleeve will be caused to turn with the rocker shaft. Bag-holding arms 12 which are of a conventional construction for holding a mail bag 13 extends from this sleeve and when in a normal posi-

105 110

tion will be disposed substantially vertically as shown in Fig. 3 so that the mail bag will be suspended in the horizontal position shown. When however, the mail bag is to be removed, the push rods 6 will be forced rearwardly and will draw upon the links or rods 8 to rotate the rocker shaft and sleeve carried thereby and swing the arms upwardly to the position shown in Fig. 4 in which position, they will hold the mail bag in the vertically disposed position. When held in this vertically disposed position, the mail bags can be removed by means of the conventional construction of bag catching means 14 mounted upon the car which latter is indicated in general by the numeral 15. In order to move the rods 6 rearwardly and swing the bag carrying arms 12 upwardly, there has been provided a push bar 20 16 which extends longitudinally of the track and has the forward end portions of the rods 6 connected with it as shown at 17. This push bar 16 has its end portions 16' curved to extend away from the track and 25 terminating in depending arm portions 18 pivotally mounted by bearings 19. Therefore, the push bar may be swung upon the pivots 19 to impart sliding and tilting movement to the rods 6. It is desired to have 30 this push bar 16 normally held in engagement with a cam strip or plate 20 which extends longitudinally of the track adjacent one of the rails 21 and therefore there has been provided pistons 22 which are slidably 35 mounted in cylinders or cases 23 and have their piston rods 24 connected with the end portions of the push bar 16 as shown in Figs. 3 and 4. Inward movement of the pistons is resisted by spring means as shown 40 at 25 and it will thus be seen that the push bar 16 will be normally held in engagement with the cam strip 20 by means of these springs 25 and held in this normal position due to the fact that the arms 12 have a 45 tendency to remain in the position shown in Fig. 3 with the lever arms 9 swung upwardly and the rods 6 held thrust forwardly by the links 8. The end portions of the cam strip 20 are curved toward the rail 21 50 so that the roller 26 can readily pass between the strip 20 and the push bar 16. This roller 26 is carried by a plunger 27 slidably mounted in a mounting 28 and yieldably held in a raised or inoperative position by 55 a spring 29. When the operator in the mail car places his foot upon the plunger 27 and pushes it downwardly, the roller will be positioned as shown in Figs. 2 and 4 so that it can pass between the strip 20 and the push 60 bar 16 and move the rods 6 rearwardly to swing the bag carrying arms upwardly to the position shown in Fig. 4 and thus support the bag in position for engagement by the bag-engaging means 14.

65 There has thus been provided a mail bag

delivering structure which is so constructed that ordinarily the bag holding means will be positioned in an inoperative position where it will be out of the way and not liable to strike passengers who may be looking out of a window of a passing train. There has further been provided a mail delivering device in which the bag holding means will be swung to the operative position when acted upon a train carried element and will return to the inoperative position as soon as the train carried element is out of engagement with the push bar forming part of the delivering structure.

We claim:

1. A mail bag delivering apparatus comprising a vertically disposed support, a rocker shaft rotatably carried by said support and disposed horizontally, bag-engaging arms extending from said shaft for swinging movement into and out of a bag delivering position when the shaft is rotated, a crank arm extending from said shaft, a pull-rod connected with said crank arm and extending downwardly and away from said rocker shaft, a push-bar for extending longitudinally of a track rail for engagement by a train-carried abutment, said push-bar having its end portions bent to extend in diverging relation to the rail and being then bent downwardly and adapted for pivotal connection with means for mounting the push-bar for swinging movement towards and away from the rail, and a push-rod connected with said push-bar and extending outwardly from the same at substantially right angles to the push-bar and connected with the lower end of the pull-rod to impart movement to the pull-rod and rotate the rocker shaft to swing the bag-carrying arms to a bag delivering position when the push bar is moved away from the track rail.

2. A mail bag delivering apparatus comprising a support including vertically disposed standards, a rocker shaft disposed horizontally and rotatably carried by said standards, bag-holding arms extending from said shaft for swinging movement into and out of a bag-delivering position when the shaft is rotated, crank arms extending from said rocker shaft, pull-rods connected with said crank arms and extending downwardly and away from the rocker shaft, supporting means for said standards, a push-bar for extending longitudinally of a track-rail and having its end portions extending in diverging relation to the rail and adapted to be pivotally mounted to mount the push-bar for swinging movement towards and away from the rail, and push-rods pivotally connected with the push-bar intermediate the length thereof and extending from the push-bar at right angles thereto and pivotally connected with the lower ends of the pull-rods.

3. A mail bag delivering apparatus comprising a vertically disposed support, a rocker shaft rotatably carried by said support and disposed horizontally, bag-engaging arms carried by said rocker shaft and extending therefrom for engaging opposite ends of a bag, a crank arm extending from said rocker shaft for imparting rotary movement to the same, a pull-rod connected 10 with said crank arm and extending downwardly from the same, a push-bar for extending longitudinally of a track rail, said push-bar having its end portions bent to extend from the rail in diverging relation 15 thereto, and being then bent downwardly, pivot brackets connected with the lower end of the downturned end portions of said

push-bar to mount the push-bar for swinging movement towards and away from the track-rail, a push-rod pivotally connected 20 with the push-bar and extending from the push-bar and pivotally connected with the lower end of said pull-rod, and spring-controlled means connected with the end portions of the push-bar adjacent the upper 25 ends of the downturned end portions thereof and serving to yieldably hold the push-bar against movement away from the track rail.

In testimony whereof we have hereunto 30 affixed our signatures.

OTHO NILE BRAUN.

LLOYD FRANK NICHOLS.

ELMER LEE UNDERWOOD.
